UNITED STATES PATENT OFFICE.

SETH WINSLOW, OF SOMERVILLE, MASSACHUSETTS.

WARDROBE-BEDSTEAD.

SPECIFICATION forming part of Letters Patent No. 235,479, dated December 14, 1880.

Application filed March 20, 1877.

To all whom it may concern:

Be it known that I, SETH WINSLOW, of Somerville, in the county of Middlesex and State of Massachusetts, have invented certain 5 Improvements in Wardrobe-Bedsteads, of which the following is a specification.

In the accompanying drawings, forming a part of this specification, Figure 1 represents a longitudinal vertical section of a bedstead 10 embodying my improvements, showing the bed-body lowered. Fig. 2 represents a similar section showing the bed-body raised. Fig. 3 represents a transverse section on the plane of line $x-x$, Fig. 1. Fig. 4 represents a section on the plane of line $y-y$, Fig. 3; and Fig. 5 represents a detached view of one corner of the bed-body.

My invention relates to that class of wardrobe-bedsteads in which the tilting or swinging bed-body is pivoted to the stationary head-frame or casing at four points—viz., by two inner pivots at the head of the bed-body and two outer pivots between the head and the center of the body—these pivots being arranged 25 in pairs and projecting outwardly from corresponding points on the opposite sides of the bed-body. The outer pivots constitute the fulcrums on which the body turns, and sustain the entire weight of the body when it is in a 30 vertical position, and support the inner end of the body when it is in a horizontal position, the inner pivots constituting sliding hinges and preventing the bed-body from being moved longitudinally away from the head-piece or 35 casing. Hence, when the outer pivots slide or run horizontally they must be located at such distance from the inner pivots, and from the floor on which the bedstead rests, as to support the bed-body at such height that when it 40 is in a vertical position its lower or inner end will not strike the floor, and when in a horizontal position it will not be so high above the floor as to interfere with its convenient use and neat appearance as a bed. These requirements, when a low or French bedstead is 45 desired, necessitate the locating of the outer pivots at points so near the inner end of the bed-body as to interfere with the desirable approximate equilibrium of the bed-body, making 50 the weight of the outer portion of the body so greatly in excess of the weight of the inner

portion as to render the operation of raising and lowering the body quite difficult.

My invention has for its object to enable the outer pivots of this class of bedsteads to be 55 located sufficiently far from the inner end of the body as to produce the desired approximate equilibrium without supporting the body at too high a point when in a horizontal position, or allowing its lower or inner end to come 60 in contact with the floor when in a vertical position.

My invention consists, essentially, of a wardrobe-bedstead provided with horizontal and inclined grooves and vertical guide-grooves, 65 in a permanent frame, adapted to combine with a movable frame provided with changeable fulcrums and certain pivots, whereby the said movable frame may be lifted and folded up to said permanent frame, as will be hereinafter more fully set forth.

In the drawings, A represents the head-piece or casing, which is composed of two vertical side pieces, A', extended forward at their bases and connected at suitable points by cross-bars. 70 The side pieces are provided at their inner sides with vertical grooves or guides B and obtuse-angled grooves or guides C, the latter being composed of horizontal portions 1 and inclined portions 2, arranged as shown in Figs. 80 1 and 2.

D represents the bed-body. E' represents the inner pivots, which are composed of friction-rollers located at the opposite ends of a cross-bar, D', extending across the head or inner end of the body. These rollers project into the grooves B, by which they are guided.

F represents the outer pivots or fulcrums, which are composed of friction-rollers located on the outer sides of the bed-body between 85 the inner end and the center thereof, and project into the guides C, as shown in Figs. 1, 2, and 3. When the bed-body is in a horizontal position the fulcrums F rest in the inclined portions 2 of the guides C, as shown in Fig. 1; 90 and when the body is in a vertical position the fulcrums rest in the horizontal portions 1 of the guides C, as shown in Fig. 2.

It will be seen that when the body D is turned upwardly the fulcrums F will move up 100 the inclines 2 and be gradually elevated thereby until they enter the horizontal portions 1,

so that when the body is in a vertical position its fulcrums are supported at a higher point than when it is in a horizontal position.

By this arrangement of the guides C, I am enabled to locate the fulcrums F comparatively near the center of the bed-body without causing them to support the bed-body at too high a point when the body is horizontal or at too low a point when it is vertical. I thus secure a closer approximate equilibrium than would be attainable if the guides C were entirely horizontal, and am enabled to secure perfect equilibrium by applying less weight to the inner end of the bed-body than heretofore in beds of this class.

The counterbalancing-weight may be applied to the inner end of the bed-body in any desired manner. I prefer to employ a metallic bar, G, which is adapted to slide in the grooves B and rest on the cross-bar D'. If desired the cross-bar D' may be made of metal and used as a weight, it being important that the weight be located at the inner edge of the body when the latter is raised, in order that the center of gravity may be kept inside of the fulcrums F.

L represents the head-board, which is applied to the side pieces, A', in any desired manner. I prefer to apply it so that it can be removed, and for this purpose locate it in the grooves B, and secure it in place by screws or other removable fastening devices.

The guides C are formed in detachable pieces H, which are provided with dowels I and elongated mortises J. The side pieces, A', are recessed to receive the pieces H, and are provided with holes to receive the dowels I, and with tenons K, which enter the mortises J. The pieces H are thus adapted to slide horizontally into the recesses in the side pieces, and when in place are prevented from moving in any direction, except outwardly, by the walls of the recesses, the dowels, and the tenons. The horizontal portions of the guides C extend to the ends of the pieces H, so that the latter

can be applied and removed while the bed-body is in a vertical position.

L' represents the swinging foot-piece that supports the foot of the bed-body, this piece being hinged to the body and adapted to swing downwardly when the body is raised, as shown in Fig. 2.

M represents a jointed brace, which extends from the bottom of the bed-body to the outer end of the foot-piece L'. One of the parts of the brace M is provided with a projection or tongue, m, and the other with a spring, m'. When the piece L' is swung outwardly and the brace M is nearly straightened the spring m' bears against the projection m and straightens the brace automatically, operating like the spring of a pocket-knife and preventing the brace from folding until the bed is lifted.

The rollers E' are supported on trunnions O, which are formed on or rigidly attached to plates P, these forming parts of angular braces P', which are attached to the corners of the body D, as shown in Fig. 5. The rollers or fulcrums F are supported on trunnions passing through the sides of the body D, as shown in Fig. 3.

The guides C may be curved instead of angular, and their lower ends may terminate in horizontal portions, if desired.

I claim—

The permanent frame of a wardrobe-bedstead provided with horizontal and inclined grooves C and guide-grooves B, in combination with the movable frame D, provided with the changeable fulcrums F and pivots E', substantially as and for the purpose set forth.

In testimony whereof I have signed my name to this specification in the presence of two subscribing witnesses.

SETH WINSLOW.
